UNITED STATES PATENT OFFICE.

FLORYJAN WAJDA, OF HAMMOND, INDIANA, ASSIGNEE OF ONE-HALF TO FRANK PAWLACZYK, OF HAMMOND, INDIANA.

RAILWAY-TIE AND FASTENER.

1,249,865.

Specification of Letters Patent. Patented Dec. 11, 1917.

Application filed October 6, 1915, Serial No. 54,384. Renewed October 5, 1917. Serial No. 194,987.

To all whom it may concern:

Be it known that I, FLORYJAN WAJDA, a subject of the Emperor of Austria, residing at Hammond, in the county of Lake and State of Indiana, have invented certain new and useful Improvements in Railway-Ties and Fasteners, of which the following is a specification.

This invention relates to certain new and useful improvements in railway tie and rail fastener.

The primary object of the invention is the provision of a combined rail holder and fastener having a ready means for securing rails in position by means of slidable inter-engaging members and without the necessity of employing screws or bolts unless desired.

A further object of the device is the provision of a tie member having rail supporting and engaging slidable interlocking members whereby the opposite rails of a railway track may be laterally adjustably positioned upon the ties of the roadbed.

A still further object is to provide stationary base members upon a roadbed, the same having longitudinally slidable ties carried thereby and adapted to retain the rails thereon by means of slidable interlocking members, it being also designed to securely retain the said ties and bases together when the track construction is completed.

With these general objects in view and others that will appear as the nature of the invention is better understood, the same consists in the novel combination and arrangement of parts hereinafter more fully described, illustrated in the accompanying drawings, and pointed out in the appended claims.

In the drawings forming a part of this application and in which like-designating characters refer to corresponding parts throughout the several views:

Figure 1 is a side elevation of the present device in its operative position, the rails being shown in transverse section.

Fig. 2 is a top plan view thereof.

Fig. 3 is an end view of the same.

Figs. 4 and 5 are transverse sectional views taken respectively upon lines IV—IV and V—V of Fig. 1.

Fig. 6 is a perspective view of the base portion of the tie member.

Fig. 7 is a perspective view of the rail-engaging slide of the tie member.

Fig. 8 is an inverted perspective view thereof.

Fig. 9 is an inverted perspective of one of the end locking blocks.

Fig. 10 is a longitudinal sectional view through an end portion of the device transversely of the rail secured therein, and

Fig. 11 is a perspective view of the locking plate detached.

Referring more in detail to the accompanying drawings, it will be noted that the invention broadly consists in a combination tie comprising a base 10 adapted to receive a slide 11 longitudinally shiftable thereon, while blocks 12 may be secured to the opposite ends of the said slide by means of the locking plates 13. The base 10 is adapted to be horizontally positioned flatly engaging the roadbed and being provided with upwardly extending opposite flanges 14 adjacent its opposite ends and having downwardly diverging opposite sides 15 adapted for the sliding reception of the slide 11, therebetween, the opposite edge faces 16 of which slide are outwardly and downwardly divergent. Longitudinal slots 17 are arranged in the opposite ends of the slide 11 having upturned oppositely projecting fingers 18 at the inner ends of the said slots and adapted to fit over the adjacent base flange 19 of the railway rail 20 when flatly seated upon the opposite end portions 21 of the said slides.

The ends of the slide 11 are positioned spaced from the opposite ends 22 of the base 10 when operatively positioned thereon and one of the blocks 12 is adapted to flatly seat upon the upper face of the base 10 at each end thereof and to slide between the base flanges 14 in the manner best illustrated in Fig. 2 of the drawings, it being noted that a projecting arm 23 is formed upon the block 12 which slidably extends within the slide slot 17, the forward face 24 of the said arm being inclined and adapted to flatly engage the inclined surfaces 25 upon the under side of the adjacent finger 18.

With the rail 20 mounted upon the slide ends 21, the block 12 may be flatly seated upon the upper surfaces of the base 10 and slid inwardly for engaging the abutment 29 of the block over the adjacent base flange

of the rail, the slightly curved free face 30 of said abutment engaging the rail web 31 and also against the under surface 32 of the rail tread.

5 When the rail is so positioned, the same is seated upon the block arm 23 and the slide ends 21, it being noted that the said last-named ends have oppositely inclined terminal faces 31 which engage similarly inclined shoulders 32 of the block 12 at opposite sides of the arm 23. Transverse slots 33 are provided on the under surface of the slide ends 21 and a similar slot 34 is provided upon the under surface of the block arm 23 10 and when the elements are operatively positioned as illustrated in Fig. 1, the plate 13 is adapted for positioning transversely through the said slots 33 and 34, thus locking the block 12 to the slide 11. The plate 13 is inserted when the end slots 33 are positioned inwardly of the adjacent end flanges 14 and after the positioning of the said plate, the slide and block are slidably forced longitudinally upon the base 10 so as to be 15 positioned between the flanges 14 thus locking the plate 13 in its engaging position between the flange faces 15.

The opposite ends of the base are similarly constructed as well as the slide and its engaging block and when the rails are thus locked in position, a bolt 35 may be positioned through the central perforation 36 of the base 10 at the underneath cut-away portion 37 of the base and screw-threaded 20 into the bottom opening 38 of the slide 11. This arrangement prevents any relative longitudinal movement between the slide 11 and the base 10, but for the purpose of more firmly locking the members together and retaining the end blocks 12 in their rail-engaging 25 positions, screws 39 are seated within perforations 40 at each end of the base 10 and outwardly of the adjacent blocks 12 which arrangement prevents any possible outward 30 unlocking movement of the blocks 12.

While the form of the invention herein shown and described is what is believed to be the preferred embodiment thereof, it is nevertheless to be understood that minor 35 changes may be made without departing from the spirit and scope of the invention as set forth in the claims.

What I claim as new is:—

1. A device of the class described comprising a base, a rail mounting slide longitudinally shiftable thereon, interengaging end blocks carried by the said base and associated with the said slide, and locking plates engaging the said slide and blocks.

2. A device of the class described comprising a base having spaced pairs of flanges adjacent the opposite ends thereof, a slide adjustably positioned between the said flanges and having longitudinal slots in its opposite ends, an oppositely projecting finger carried at each end of the slide adjacent the inner ends of the said slots, end blocks slidably positioned between the said flanges outwardly of the said slide and having inwardly projecting arms seated within the said slots, inwardly extending abutments carried by the said blocks oppositely positioned with respect to the adjacent one of said fingers, interengaging lock plates between the said blocks and slides, and movement-preventing means between the said blocks and base.

3. A device of the class described comprising an elongated base adapted to be positioned upon the railroad bed and having approaching side flanges adjacent the opposite ends thereof and being further provided with a hollowed-out centrally arranged under portion, a slide having outwardly tapered edges shiftably positioned and guidingly arranged upon the said base between the said flanges and having an open longitudinal slot at each end thereof forming spaced end portions, the said end portions being provided with alining transverse slots 80 upon their under sides and the ends of said end portions being oppositely inclined, outwardly extending flange-engaging fingers carried by the said slide adjacent its opposite ends and having inclined inner faces, 85 blocks slidably arranged between the said flanges and having inwardly extending arms removably positioned between the said end portions of the slide and having inclined free ends engaging the said inclined faces of the said fingers, the said arms having transverse slots upon their under sides clamping plates transversely positioned within the said slots of the said arms and end portion slots, inwardly-extending flange-engaging 90 abutments carried by the outer ends of the said blocks positioned opposite the said fingers when the device is assembled, and retaining screws positioned adjacent the opposite ends of the said base outwardly of the 95 said blocks.

In testimony whereof I affix my signature in presence of two witnesses.

FLORYJAN WAJDA.
